PACKAGING MACHINE

Charles C. Clapp, Tacoma, Wash., assignor to Weyerhaeuser Timber Company, Tacoma, Wash., a corporation of Washington

Application July 23, 1956, Serial No. 599,438

16 Claims. (Cl. 53—14)

This invention relates to a method and apparatus for packaging articles, and, although the invention is not to be limited to the packaging of a specific product, it is described herein in connection with the packaging of a fuel product known on the market as "Pres-to-Logs." Such fuel product, made chiefly for fireplace use, is cylindrical in shape and is formed by compressing sawdust containing a natural or added binder.

A principal object of the present invention is to provide a novel method and apparatus for wrapping a plurality of articles together in a common package.

Another object is to provide an improved method of applying and securing a single flat wrapper to a plurality of objects to form a break-apart package.

Another object is to provide an improved packaging machine which applies and secures a wrapper in one direction around a plurality of articles to form an open-sided package.

More specific objects are to provide a packaging machine having means for perforating a wrapper in longitudinal lines and means for applying glue lines to the wrapper on both sides of the perforation lines for adhering articles of manufacture to said wrapper parallel to said perforations whereby a single article and its wrapper portion can be torn from the package; to provide a machine arranged to drop articles to be packaged on a suspended wrapper whereby a partial folding of the wrapper is accomplished by the weight of the article; and to provide a combination off-bearing conveyor and press means which carries the package to an unloading station and which applies pressure to glue joints between the package and articles therein while the package is traveling to said unloading station.

Still another object of the present invention is to provide control means for an electrical and pneumatic system for efficiently governing the performance of a series of operations in sequence in a packaging operation.

In the present packaging machine, elongated flat wrapper blanks are moved individually from the bottom of a stack of the blanks in a longitudinal direction into perforating means which act to apply full length perforation lines to the blanks and to feed the blanks through glue rollers which apply longitudinal glue lines to the wrapper on each side of the perforation lines. The perforating means also feeds the wrapper blanks into pairs of beveled rollers which transversely curve the blanks to impart longitudinal rigidity thereto and which project the blanks in such rigid condition onto spaced supports above the floor of a wrapping station. The articles to be packaged are fed to the wrapping station and positioned above the projected blank in parallel superposed relation to the glue lines so that when released they fall by gravity on the blank. The impact of the articles falling on the blanks partially folds the blanks, and the remainder of the folding operation is accomplished by a pusher mechanism which also is operative to move the completed package into an off-bearing conveyor.

2

In the final folded condition of the wrapper the glue lines extend longitudinally around the articles, and the off-bearing conveyor has pressure applying means operative on the wrapper over the glue lines for forming an integral connection between the open-sided package and the articles therein so that the articles will not fall out. When the need for an individual article arises, the wrapper can be torn along the perforated lines to separate said article from the rest of the package, together with its wrapper portion. When the article so wrapped comprises artificial log fuel, the wrapper is preferably formed of cardboard whereby the portion of the wrapper which is adhered to each article can be used to assist in igniting the logs.

15 The invention will be better understood and additional objects and advantages will become apparent from the following description taken in connection with the accompanying drawings which illustrate a preferred form of the invention. It is to be understood, however, that the invention may take other forms, and that all such modifications and variations within the scope of the appended claims which will occur to persons skilled in the art are included in the invention.

In the drawings:

25 Figure 1 is a perspective view of a completed package formed by the method and apparatus of the present invention;

Figure 2 is a plan view of a wrapper blank for forming the package of Figure 1;

30 Figure 3 is a longitudinal sectional view of the packaging machine for forming the package shown in Figure 1, taken on the line 3—3 of Figure 4;

Figure 4 is a top plan view of the machine;

Figure 5 is a sectional view taken on the line 5—5 of Figure 3 showing the bevel roller assembly for curving the blanks;

Figure 6 is a fragmentary elevational view of the wrapping station, with certain parts in section, showing a wrapper blank partly folded around the articles;

40 Figure 7 is a fragmentary elevational view similar to Figure 6 but showing a final folding step;

Figure 8 is a sectional view taken on the line 8—8 of Figure 4, showing feed means for delivering a predetermined number of articles to the wrapping station;

45 Figure 9 shows a wiring diagram for drive motors of the machine;

Figure 10 shows a wiring diagram of the electrical system for controlling the operation of the machine; and

50 Figure 11 is a diagrammatic illustration of the fluid pressure system which performs various operations in the machine.

The packaging machine and method of the present invention form a unit package P for a plurality of objects, as shown in Figure 1. The wrapper for this package, designated by the reference character W, is shown in blank form in Figure 2. This wrapper and the unit package P per se form no part of the present invention. The wrapper W is illustrated herein for the packaging of cylindrical articles A, such as the wood fuel product referred to on the market as "Pres-to-Logs," and are formed of a bendable and combustible material, such as a corrugated cardboard or similar material.

Referring specifically to Figure 2, the wrapper blank W has a plurality of transverse pre-formed crease lines 15, 16, 17 and 18. In the completed form of the package, this wrapper is folded on its crease lines to form a bottom wall 20, a top wall 21, a pair of end walls 22, and an upper flap member 23. As will be more fully described hereinafter, the wrapper is provided, by the operation of the machine, with longitudinal perforation lines 24 intermediate the articles A, as shown in Figure

1, whereby one of the articles, together with its wrapper portion, may be torn from the rest of the package. Each of the individual articles A is glued to the wrapper by glue lines 25 extending longitudinally entirely around the article so that each article is permanently united with its separable wrapper portion.

The machine for forming the package of Figure 1 comprises a supporting framework having longitudinal angle members 28, transverse angle members 29, and upright side support members 30. At one end of the machine is a magazine or hopper 32 for wrappers having upstanding angle corner members 33 and a front wall 34 having a bottom slot 35 through which a single wrapper W may be ejected at a time. A wiper blade 36 hinged at its upper edge is disposed across the transverse slot 35 and is adapted to engage the upwardly facing surface of the wrappers for the purpose of holding the wrappers back so as to allow only one wrapper blank at a time to feed out and for removing any paper fragments or other foreign matter which may be present on the wrappers.

The bottom wall of the hopper 32 comprises a supporting plate 40, or other suitable supporting means such as longitudinal bars. As best seen in Figure 4, the plate 40 has longitudinal slots 41 and 42 joined by a restricted throat portion 43 which forms a guide for a feed arm 45. The arm 45 has a U-shaped head 47 carrying a plurality of upwardly projecting teeth or sharpened pins 48, the teeth 48 being engageable with the lowermost wrapper W and being forwardly inclined so that when the arm 45 moves toward the front of the magazine, a wrapper will move therewith. In the return, or leftward movement, of the arm 45, the angularity of the teeth permits the head to slide freely under the lowermost wrapper. The head 47 has transversely projecting pins 50 slidably in grooves 51 in the side walls of the slot 41. The height of the grooves 51 is greater than the pin diameter, whereby the head 47 is adapted to be lifted slightly at predetermined times to a position whereby the teeth 48 positively frictionally engage the lowermost wrapper.

The end of the arm 45 opposite from the head 47 is pivotally mounted on a transverse pin 55 slidably mounted in grooves 56 in the side walls of slot 42. Pin 55 carries one or more downwardly depending ears 56 to which is pivotally attached a pitman 57 connected to a crank arm 58 keyed to a shaft 60. Also keyed to the shaft 60 are a sprocket wheel 62, shown in dotted lines in Figure 3, and a switch-actuating wheel 64 having a pair of knobs or projections 65 and 66 on one side thereof. The two knobs are at different radial distances from the center of the wheel 64 and are engageable with switch arms 68 and 69 of micro-switches 70 and 71, respectively, the purpose of which will be described hereinafter. When the machine is in operation and the wheel 64 is rotating, the knobs 65 and 66 engage and move past their respective switch arms to momentarily close the switches. The shaft 60 in Figure 3 projects toward the observer from the wheel 64 and the crank arm 58, which is keyed to said shaft, is spaced sufficiently from the wheel to clear the switches 70 and 71.

The pitman 57 carries an upstanding compression spring 72 on a stud 73, and this spring is located in a predetermined position on the pitman and is of a predetermined length so as to be engageable with the under surface of the head 47 only when the crank arm 58 is moving through its upper arc. In this upper arcuate movement of the crank arm, the pitman draws the arm 45 through its forward stroke, and, in this forward stroke, the spring 72 engages the head 47 wherein the head 47 is biased upwardly to a point where the transverse pins 50 engage the top of the side grooves 51. Such upward movement of the head 47 insures a positive gripping of the lowermost wrapper by the teeth 48 during each feed stroke.

Sprocket 62 on the shaft 60 is driven by a chain 75 engaged with one wheel of a double sprocket 76 keyed

to a shaft 77. Shaft 77 is driven by a chain 79 engageable with the other sprocket wheel 76 and a sprocket 80 keyed to a shaft 81. Sprocket 80 is in turn driven by a chain 83 engageable with a sprocket 84 driven by an electric motor 85. The direction of rotation of this drive mechanism is clockwise as indicated by the arrow adjacent the switch actuator wheel 64.

Also keyed to the shaft 77 is a sprocket wheel 90 engaged by a chain 91 which transmits power to a sprocket 92 keyed to a shaft 93 and a sprocket 94 keyed to a shaft 95, these three sprockets being shown in dotted lines in Figure 3. Also keyed to the shaft 95 is a gear 97, also shown in dotted lines in Figure 3, and a pair of lower perforating wheels or rolls 98 having a plurality of pins 99 on their peripheral edges, only one of such wheels being shown in Figure 3. Also keyed to the shaft 93 is a gear 100.

Disposed above the shaft 95 is a shaft 102 to which is keyed a sprocket 103 and a pair of upper perforating wheels, or rolls 105, having projecting pins 106 on their peripheral edges. The wheels 105 are disposed directly over the wheels 98, and the perforating pins in each pair of upper and lower wheels are staggered so as to intermesh when the wheels rotate, the space between the wheels, exclusive of the teeth, being substantially the thickness of a wrapper W. The wheels 98 and 105 are adapted to provide the wrapper W with the perforation lines 24 by means of which individual articles A can be torn, together with its portion of the wrapper, from the remaining part of the package. The lower perforating wheels 98 are rotatable in a clockwise direction and the upper wheels 105 are rotatable in a counter-clockwise direction whereby when driven by the motor 85, they are adapted to feed a wrapper to the right into the machine. These wheels thereby serve the dual purpose of feeding and perforating the wrappers.

Mounted on a stub shaft 110 and meshing with the gear 103 on the shaft 102 is an idler gear 111. This gear also meshes with a large gear 113 keyed on a shaft 114, which also has keyed thereto three glue-applying rollers 115, it being noted, as viewed in Figure 4, that the rollers 115 are in staggered relation relative to the perforating rollers 98 and 105 so that in the operation of the machine, the glue lines 25 are applied parallel to the perforation lines 24 but offset therefrom. The glue-applying rollers 115 are in surface contact with a glue supply roller 118 on a shaft 119 on which is keyed a gear 120 in meshing engagement with the gear 113. Roller 118 projects into the side of a glue pot 125 and picks up glue therefrom and deposits it on the rollers 115. The bottom plate 40 for the magazine 32 extends into the machine below the rollers 115 and these rollers are disposed above the plate 40 a distance substantially equal to the thickness of the wrappers, whereby, when the perforating wheels 98 and 105 move a wrapper between the rollers and the plate 40, three glue lines 25 will be applied to the upper surface of the wrappers.

Disposed above the shaft 93 is a shaft 127 having a gear 128 keyed thereto which is in meshing engagement with the gear 100 on the shaft 93. Keyed to the shaft 93 are a pair of bevel rollers 130, and keyed to the shaft 127 are a pair of bevel rollers 131. As best seen in Figure 5, the bevel portions of the rollers 130 and 131 incline downwardly toward a point between the rollers and, when the wrapper is engaged by these pairs of rollers, the portion thereof which has moved through the rollers will be curved into a trough-shape. This transverse curvature of the wrapper gives it longitudinal rigidity, and the portion which has proceeded through the rollers will be projected rigidly in a straight line. As seen in Figure 3, the rollers 131 are slightly offset to the left relative to the rollers 130, whereby, in addition to causing the wrapper to assume a curved shape in cross section, these rollers direct the wrapper upwardly at a

slight inclination. A wrapper W is shown in Figure 3 completing its movement through the bevel rollers.

Disposed in longitudinal relation to the machine frame is a double acting fluid pressure operated cylinder 135 having fluid pressure pipes 136 and 137 connected to opposite ends thereof and having a plunger 138 equipped with an upright head plate 139 having a top forwardly bent lip 140. The operation of the cylinder 135 is controlled by a four-way valve actuated by the switches 70 and 71, to be described in connection with the electrical and pneumatic systems.

Disposed adjacent the bevel rollers 130 and 131 is a wrapping station 145 and associated with this wrapping station is a magazine or hopper 146 supported on upright frame members 147 and comprising a channel-shaped chute or guideway 148 inclined slightly toward the wrapping station. The chute 148 comprises a gravity fed conveyor for feeding the articles A into the wrapping station in longitudinal alignment with the machine, and disposed at the lower end of the conveyor 148 are a pair of side trip plates or flaps 150 of a length sufficient to support three articles A at a time. The trip plates 150 are secured to transverse shafts 152 having pinion gears 153 on one end in mesh with upright racks 154 supported at opposite ends of an arm 156. Arm 156 is centrally pivotally connected to a piston rod of a single acting fluid pressure operated cylinder 158.

Cylinder 158 has a fluid pressure pipe 160 connected to its lower end, and the operation of this cylinder is controlled by a solenoid operated valve, to be described, in turn controlled by a switch 162 mounted on a transverse frame member 161 and having an arm 163 adapted to be engaged by a wrapper which is being forwardly projected in a rigid condition from the bevel rollers 130 and 131. Engagement of the arm 163 by the forward edge of the wrapper closes the switch 162 which causes the operation of the cylinder 158 whereby the arm 156 and racks 154 move upwardly to rotate the two pinions 153 in opposite directions for pivoting the trip plates 150 downwardly and causing the three articles A on the trip plates to drop into the packaging station. Arm 156 is biased downwardly by a tension spring 164 connected between said arm and the machine frame.

Referring specifically to Figure 8, a magazine unloading arm 168 is pivotally mounted at 169 on the lower side of the chute 148 and has a pair of upstanding fingers 170 and 171 adapted to project one at a time through suitably spaced apertures 172 in the bottom wall of the chute. The end of the arm adjacent the finger 170 is pivotally connected to a piston rod of a fluid pressure operated cylinder 173 having a fluid pressure pipe 174 connected to the bottom thereof and being pivotally connected to one of the frame members 28. The piston rod is normally retracted in the cylinder 173, but, when fluid pressure is admitted to the cylinder, the outward movement of its piston rod pivots the arm 168 clockwise to move the finger 170 upwardly through an aperture 172 and between a pair of articles A. This pivotal movement of the arm 168 causes the finger 171 to move downwardly below the bottom wall of the chute to permit the articles up to the finger 170 to roll downwardly onto the trip plates 150, the spacing of the fingers 170 and 171 being such as to permit three articles A to be deposited on the trip plates at a time. In the upward position of the finger 170 the articles in the magazine are held back thereby, and, when the piston rod is retracted in its cylinder, the articles in the magazine will roll down into engagement with the finger 171, as shown. A compression spring 175 is disposed between the arm 168 and the bottom wall of the chute 148 adjacent the finger 170, and this spring biases the arm 168 in a counterclockwise direction. Operation of the cylinder 173 is controlled by a switch 180, Figure 3, having an arm 181 projecting into the path of the plunger 138, whereby, when the plunger reaches substantially its outward stroke position, it closes the switch

and causes the cylinder 173 to pivot the arm 168 and allow three articles to roll down onto the trip plates 150.

Mounted on the upright frame members 147 is a transverse bar 183 carrying a pair of shoes 184 which are disposed in predetermined spaced relation so as to be located between the glue lines 25 of a wrapper W projecting through the wrapping station, best seen in Figure 4. Also mounted transversely of the machine on upright frame members 186 is a transverse bar 187 to which are secured three longitudinally disposed parallel straps 188. The straps 188 have the same transverse spacing as the three glue lines on the wrapper and are biased downwardly by a plurality of springs 190 compressed under longitudinal rigid frame members 191 mounted under frame members 161. In one of the final steps of the package-forming operation, the wrapped packages P are moved under the spring-pressed straps 188 which apply pressure to the glue lines and cause the glue to unite the surfaces to be joined together.

At the end of the machine is a conveyor 194 comprising a pair of pressure belts 195 and 196 disposed in vertically spaced relation. Belt 195 passes over rollers 197 keyed to a shaft 198, and belt 196 passes over rollers 199 keyed to a shaft 200. Shaft 200 has a sprocket 202 thereon engaged by a drive chain 203 from a drive motor 204. Also keyed to the shaft 200 is a gear 206 meshing with a first idler gear 207, in turn meshing with an idler gear 248. Idler gear 208 meshes with a gear 209 on the shaft 198, whereby a drive connection is established between the two shafts 198 and 199. Spring-pressed rollers 210 engage the inner runs of belts 195 and 196 and apply pressure to the packages being pushed through the pressing device to set the glue in glue lines 25. The length of the conveyor 194 is such as to produce a pressure on the glue lines for a time sufficient to permit the glue to set. Heat may also be applied, if desired, if a heat and pressure sensitive glue is used.

Referring now to the electrical system, Figure 9 shows the wiring diagram for the machine drive motor 85 and the conveyor motor 204. The motors are energized by line wires 213 and 214. Connected to one of the line wires are a pair of normally closed switches 215 and 216, and these switches are located at each end of the belt conveyor for convenience in shutting off the conveyor when desired. Connected to the line 213 is a start switch 217, and connected between the switch 217 and the conveyor motor 204 is a wire 218 leading to the motor 85. With this arrangement, it is apparent that upon the opening of any one of the switches 215, 216 or 217, the conveyor motor 204 as well as the machine drive motor 85 will be de-energized so that when the conveyor motor is de-energized, the drive motor 85 cannot cause packages to be moved into the conveyor. In series with the wire 218 are three switches 220, 221 and 222 which, if opened, will de-energize the machine drive motor 85 without stopping the conveyor motor.

Referring to Figure 10 there is shown an electrical system for controlling the operation of the fluid system, having a pair of supply wires 224 and 225, each provided with a master switch 226. The supply wire 224 is connected to one contact of the switch 162, and the other contact of this switch is connected to a wire 228 in turn connected to the supply wire 225 through the coil of a solenoid 229. Wire 224 is also connected to a contact of switch 70 operable by the switch arm 68. The other contact of switch 70 is connected to one end of the coil of the solenoid 232 having its other end connected to the supply wire 225. The wire 224 is also connected to a contact of switch 71 operable by the arm 69, and the other contact of this switch is connected to one end of a coil of a solenoid 235, the other end of this solenoid coil in turn being connected to the supply wire 225. Supply wire 224 has branch connections 238 and 239 which bypass the switches 70 and 71, respectively, and normally open push button switches 240 and 241 are

provided in the lines 238 and 239, whereby circuits can be established around the switches 70 and 71, if desired. Solenoids 232 and 235 control the operation of the plunger 138 of the cylinder 135 in opposite directions, as will be more fully described hereinafter, and the closing of either of the manual switches 240 or 241 will energize the coil of its respective solenoid to operate the plunger in the cylinder in one direction or the other.

Supply wire 224 is connected to one contact of the switch 180 and the other contact of this switch is connected to the coil of a solenoid 243. A branch line 245 having a normally open push button switch 246 therein bypasses the switch 180 whereby, if the switch 246 is manually closed, the solenoid 243 will be energized.

Figure 11 shows in detail the fluid pressure system for operating the cylinders 135, 158 and 173. The fluid pressure pipes 136 and 137 of the cylinder 135 lead to a four-way valve 248 of conventional construction, having a pressure connection at 249 and a spool-type balanced valve member 250 to connect the fluid pressure supply with one or the other of the pipes 136 or 137. The pipe 136 or 137, whichever is not connected with pressure, communicates with an exhaust pipe 252 or 253, respectively. The valve member 250 is actuated in one direction by the solenoid 232, and is actuated in the other direction by the solenoid 235. When the pin 66 on the switch actuator wheel 64 engages switch arm 69 of switch 71, the coil of solenoid 235 is momentarily energized to cause the valve member 250 to be positioned so that fluid under pressure is admitted through pipe 136 to the back end of the cylinder 135 for causing the plunger to move outwardly. When the coil of relay 232 is momentarily energized by the engagement of switch arm 68 by its pin 65, the valve member 250 is moved the other way and fluid pressure is admitted to the front of cylinder 135 to retract the plunger. Valve member 250 always remains in its last position after the actuating solenoid is de-energized.

The solenoid 229 is adapted to actuate a two-way valve 255 which controls the operation of the cylinder 158 in turn operating the trip plates 150. The valve 255 has a balanced spool-type valve member 256 and this valve is connected to the pipe 160 leading from cylinder 158, the fluid pressure supply pipe 249, and an exhaust pipe 258. When the coil of solenoid 229 is energized, the valve member 256 is positioned so that fluid pressure is admitted to the bottom of cylinder 158 to drive the piston rod upwardly for operating the trip plates. A spring 260 is provided in the valve 255 for returning the member 256 to its rest position for exhausting the pressure from cylinder 158.

The solenoid 243 controls the operation of a two-way valve 262 connected to the pipe 174 leading to the bottom of the cylinder 173 and also connected to the fluid pressure supply pipe 249 and an exhaust pipe 263. When the coil of solenoid 243 is energized, the valve 262 causes fluid to be admitted to the bottom of cylinder 173 for pivoting the arm 168 in a clockwise direction and permitting three of the articles A to roll down onto the trip plates. When solenoid 243 is de-energized, the valve is spring-returned to exhaust position as in valve 255.

Method and operation

In the normal operation of the machine, all the switches 215, 216, 217, 220, 221 and 222 are closed and the two motors 204 and 85 run continuously. If any one of the switches 215, 216 or 217 is opened, both motors will be stopped, and if any one of the switches 220, 221 and 222 is opened, the machine drive motor 85 will be stopped but the conveyor motor will continue to operate. In the rest position of the machine in normal packaging functions, all the mentioned switches will be closed except the starting switch 217, so that, to place the motors in operation, the operator need only close this latter switch.

When the operator closes the switch 217 the drive motors are energized to cause the chains 79 and 91 to be driven, which in turn cause the operation of the pitman 57, the switch actuator wheel 64, the perforating wheels 98 and 105, the glue-applying rollers 115, the glue supply roller 118 and the bevel rollers 130 and 131. In the position of the parts shown in Figures 3 and 4 the crank arm 58 is moving through its lower arcuate travel, causing the pitman 57 to retract the feed arm 45 in readiness to move the lowermost wrapper W outwardly. In this same position of the parts the plunger 138 in the cylinder 135 is retracted and three articles A are supported on the trip plates 150. A wrapper W is disposed in the wrapping station 145 and the forward end thereof is moving into engagement with the switch arm 163 of switch 162, as shown in Figure 3.

When the wrapper in the wrapping station engages the arm 163, the switch 162 is closed for energizing the coil of relay 229 which actuates the valve 255 and fluid flows to the bottom of cylinder 158 through the pipe 160. The piston rod in the cylinder 158 is driven outwardly for moving the arm 156 and racks 154 upwardly to rotate the trip plates 150 downwardly and cause the three articles thereon to fall onto the wrapper. After the fluid pressure to cylinder 158 is cut off, the spring 164 retracts the piston rod in the cylinder 158 to cause the trip plates 150 to rotate upwardly and be in a position to receive three more articles.

Figure 6 shows the articles in their dropped position and, as the articles so move to their dropped position, they carry the wrapper downwardly into engagement with the floor of the wrapping station, the creases 16 and 17 being disposed at this time in vertical alignment with the ends of the articles so that the package will be partially formed. One end of the wrapper engages the edge of lip 140 of the pusher plate 139, and the other end of the wrapper engages the transverse bar 187.

As one of the wrappers W is being folded around the articles, as described, rotation of the shaft 60 has caused the pitman 57 to move another wrapper into the perforating rolls. Also, at this time the pin 66 on the switch actuator wheel 64 moves into engagement with the arm 69 of switch 71 to close this switch for energizing the coil of solenoid 235. When the coil of this solenoid is energized, it actuates the valve 248 to cause fluid under pressure to flow to the rear end of the cylinder 135, whereby the plunger 138 will be moved outwardly. The head plate 139 is of predetermined height so that the lip 140 folds the flap 23 over the upper end of the articles, as shown in Figure 7, this view showing the articles moved part way through the wrapping station with a flap 23 being folded on its crease 15.

As the articles move to the Figure 7 position, the forward or leading end of the package moves under the transverse bar 187 which causes the wrapper to be folded back on its crease 18, the upwardly projecting portion of the wrapper engaging the shoes 184 on the bar 183, it being remembered that the shoes 184 are spaced so as to be between the glue lines 25. Additional movement of the plunger moves the package under the straps 188 to fold the top 21 of the wrapper down on the articles and on the flap 23, and, about this time, the plunger 138 engages the arm 181 of switch 180 which closes the circuit to the coil of relay 243 to actuate the valve 262 and cause the cylinder 173 to drive its piston rod upwardly and allow three more articles to roll down on the trip plates 150 for the next packaging operation.

When the plunger 138 has reached the end of its stroke, the package has been pushed under the hold-down straps 188. At this same time, the pin 65 on the switch actuator wheel 64 engages the arm 68 of switch 70 for energizing the coil of solenoid 232 which actuates the valve 248 to supply fluid to the front end of the cylinder and retract the plunger. The next wrapper which has been proceeding through the perforating rolls is driven by said

rolls under the glue-applying rolls 115 and into the bevel rollers 130 and 131 which warp and move the wrapper forwardly through the wrapping station into engagement with the switch arm 63 for repeating the next cycle of operation. The packages P move from under the straps 188 to the belt conveyor mechanism 194 and this conveyor is preferably of a length to maintain a pressure on the glue lines a sufficient length of time to set the glue.

It will thereby be seen that the present machine provides a continuous method of feeding, perforating and gluing a carton wrapper, then folding the wrapper around a plurality of articles and conveying the unit under pressure to a desired place. The package formed is open sided and individual articles can readily be separated from the rest of the package by tearing along a suitable perforation line 24. When the article being packaged comprises a fuel product, the wrapper portion, which is removed from the package with an article therein, can be used to assist in igniting the article.

Having now described my invention and in what manner the same may be used, what I claim as new and desire to protect by Letters Patent is:

1. A machine for wrapping an elongated article comprising means for applying a glue line longitudinally along one face of an elongated wrapper blank, means for depositing an article longitudinally on said glue line, means for transversely folding said wrapper around both ends of said article and over the top thereof, and means for pressing said wrapper against said article on said glue line.

2. A machine for wrapping articles comprising means for forming spaced parallel tear lines in a wrapper blank, means for applying parallel strips of glue to one face of said wrapper on both sides of said tear lines, means for depositing a separate article on each of said glue strips, and means for folding said wrapper around said articles.

3. A machine for wrapping elongated articles in elongated wrapper blanks comprising means for forming parallel longitudinal tear lines in said blank, means for applying parallel longitudinal strips of glue on opposite sides of said tear lines, means for applying a separate article longitudinally on each glue line, and means for folding said blank transversely around the ends of said articles to overlie opposite sides thereof.

4. A machine for wrapping articles comprising power driven perforating rolls arranged to perforate a wrapper in parallel spaced lines and to drive said wrapper in said machine, means for applying strips of glue to one face of said wrapper on both sides of said perforation lines, means for depositing a separate article on each of said glue strips, and means for folding said wrapper around said articles.

5. A machine for wrapping articles comprising power driven perforating rollers arranged to perforate a wrapper in parallel spaced lines and to drive said wrapper partly through said machine, means for applying glue lines to one face of said wrapper on both sides of said perforation lines, a wrapping station, means operable on said wrapper to move said wrapper into said wrapping station after disengagement thereof by said perforating rollers, means at said wrapping station for depositing a separate article on each of said glue strips, and means for folding said wrapper around said articles.

6. An article packaging machine comprising a magazine for stacked wrapper blanks, means for sliding a single wrapper blank at a time from the bottom of said magazine, perforating rolls in the path of movement of said wrapper adapted to perforate said wrapper in parallel spaced lines, means for applying glue lines to one face of said wrapper on both sides of each line of perforations each of said glue lines serving to receive and fix a separate article, a wrapping station, means operable on said wrapper for moving said wrapper into said wrapping station, article depositing means above said wrapping station for supporting a predetermined number of articles

above said wrapper and depositing said articles by gravity on said wrapper, and means for folding said wrapper around said articles.

7. A machine for wrapping elongated articles comprising means for longitudinally feeding individual elongated wrapper blanks, means for forming parallel longitudinal tear lines in said wrappers, means for applying longitudinal glue lines to the upper face of said wrappers on both sides of said tear lines, article depositing means for supporting a predetermined number of articles longitudinally disposed in side by side relation above a wrapper and arranged to deposit said articles on the upper face of said wrapper, means for folding said wrapper transversely around the ends of said articles, and press means for adhering said articles to said wrapper at said glue lines.

8. A machine for wrapping articles comprising means for applying parallel glue lines to wrappers for said articles, a wrapping station having a floor, means to project said wrappers individually into said wrapping station above said floor surface, article feed means disposed above said wrapping station, said article feed means being arranged to support a number of articles equal to the number of glue lines on said wrapper, means in said article feed means for releasing said articles simultaneously for depositing them on said wrapper in engagement with said glue lines, and means for folding said wrapper around said articles.

9. A machine for wrapping articles comprising a wrapping station having a floor, means to move a wrapper for said articles into said wrapping station, support means at opposite ends of said wrapping station for suspending said wrapper above said floor, transverse feed means for, said articles adapted to support a predetermined number of articles over said suspended wrapper, release means on said feed means adapted to drop said articles on said wrapper for forcing the wrapper downwardly to said floor and partially folding said wrapper around said articles, and control means engageable by said wrapper for actuating said release means.

10. A machine for wrapping articles comprising a wrapping station having a floor, means to move a wrapper for said articles into said wrapping station, a transverse support member at one end of said wrapping station arranged to underlie said wrapper, a plunger normally disposed at the other end of said wrapping station, a transverse lip on said plunger arranged to underlie said wrapper, support means adapted to support articles to be packaged above said wrapper and adapted to release said articles for depositing them on said wrapper, said articles when deposited on said wrapper forcing said wrapper to said floor between said transverse support member and said lip, said downward movement of said wrapper between said transverse support member and said lip partially folding said wrapper around said articles.

11. A machine for wrapping articles comprising a wrapping station having a floor, means to move a wrapper for said articles into said wrapping station, a transverse support member at one end of said wrapping station arranged to underlie said wrapper, a plunger normally disposed at the other end of said wrapping station, means for driving said plunger through said wrapping station, a transverse lip on said plunger arranged to underlie said wrapper, article supporting members above said wrapping station for suspending said articles to be packaged above said wrapper and adapted to release said articles for depositing them by gravity on a wrapper supported in said wrapping station, said articles when deposited on said wrapper forcing said wrapper to said floor whereby said downward movement of the wrapper between said transverse support and said lip on the plunger partially folds said wrapper around said articles, and means to drive said plunger through said wrapping station to fold portions of the wrapper around said articles.

12. In an article packaging machine, a wrapping sta-

tion having a floor, means to move a wrapper for said articles into said wrapping station, support means at opposite ends of said wrapping station for suspending said wrapper above said floor, a transverse chute extending into said wrapping station, a pair of trip plates at the end of said chute adapted to support a predetermined number of articles, drive means associated with said trip plates for rotating said plates between a position for holding said predetermined number of articles above said suspended wrapper and a position for dropping said articles on said wrapper, a pivoted arm adjacent said chute, and spaced fingers on said arm projecting into said chute for passing said predetermined number of articles onto said trip plates upon pivoted movement of said arm.

13. In a packaging machine for wrapping articles, a magazine for holding a plurality of wrappers, a reciprocating feed arm for removing a single wrapper from said magazine at a time, drive means for said feed arm, means for perforating said wrappers in longitudinal parallel lines, means for applying longitudinal glue lines on each side of said perforation, a wrapping station, article holding means at said wrapping station adapted to deposit articles by gravity longitudinally on the glue lines on said wrappers, article supply means for feeding articles to said holding means, a reciprocating plunger adjacent said wrapping station adapted to fold said wrapper around said articles, means operated by said feed arm drive means for controlling the reciprocating movement of said plunger, means operated by said plunger for controlling the operation of the article supply means, and means operated by a wrapper in said wrapping station for actuating said article holding means.

14. A method of wrapping elongated articles comprising perforating an elongated wrapper along longitudinal parallel lines, applying longitudinal strips of glue on one

face of said wrapper on each side of said perforation lines, depositing an article to be packaged on each of said glue lines in longitudinal contact therewith, and folding said wrapper transversely around the ends of said articles.

15. A method of wrapping a plurality of flat ended cylindrical articles in a single package comprising perforating a flat wrapper blank along parallel lines, applying strips of glue on one face of said wrapper on each side of said perforation lines, suspending said wrapper by spaced supports, depositing said articles by gravity on each of said glue lines intermediate said supports for lowering said wrapper and partially folding it around the ends of said articles, thereafter folding said wrapper around the remaining portion of said articles, and subsequently applying pressure to said wrapper at said glue lines.

16. The article packaging machine of claim 12 in which the means to move the wrapper for said articles into said wrapping station includes a double pair of beveled rollers disposed in transversely spaced relation adjacent said wrapping station relative to the direction of feed movement, said pairs of rollers being beveled in opposite directions for feeding said wrapper into said wrapping station in a transversely warped longitudinally rigid condition.
